UNITED STATES PATENT OFFICE.

RUDY HILGEDICK, OF CHICAGO, ILLINOIS.

IRONER.

Application filed March 14, 1927. Serial No. 175,180.

My present invention has for its object to provide a simple and highly efficient ironer.

The hand-operated electric sadiron now commonly used is most efficient for its wide range of doing all classes of work and certain kinds of work that cannot be accomplished otherwise.

It is well known that very little effort is required to move a hot sadiron over an object being ironed, but it is very laborious work to lift the sadiron and carry the same from the work to a supporting stand and from said stand to the work.

By the use of my invention, this laborious work is eliminated and said invention also provides power means for imparting the to and fro movements to a sadiron.

Generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of the invention with some parts broken away and sectioned;

Fig. 2 is a fragmentary rear elevation of the turnable top section and parts mounted thereon, as shown in Fig. 1;

Fig. 3 is a plan view of the invention as shown in Fig. 1, with some parts removed;

Fig. 4 is an enlarged view in side elevation of the sadiron and parts connected thereto, and also showing certain of said parts and the sadiron in different positions, by means of broken lines;

Fig. 5 is a view in transverse section taken on the line 5—5 of Fig. 4;

Fig. 6 is a transverse vertical section taken on the line 6—6 of Fig. 1, on an enlarged scale;

Fig. 7 is a detail view in section taken on the line 7—7 of Fig. 4;

Fig. 8 is a detail view taken on the line 8—8 of Fig. 7;

Fig. 9 is a detail view with some parts sectioned on the irregular line 9—9 of Fig. 4;

Fig. 10 is a detail view with some parts sectioned on the line 10—10 of Fig. 2, on an enlarged scale;

Fig. 11 is a fragmentary detail view with some parts sectioned on the line 11—11 of Fig. 9;

Fig. 12 is a detail view in section taken on the line 12—12 of Fig. 8; and

Fig. 13 is a detail view in section taken on the line 13—13 of Fig. 8.

The numeral 14 indicates an ironing table, 60 the top 15 of which affords a smooth flat ironing surface. This table top 15 at its rear end has a turnable section 16 pivotally mounted on a heavy bracket 17 on said table top for horizontal swinging movement in 65 the plane of said table top. The joint between the table top 15 and its turnable section 16 is on the arc of a circle, the center of which is at the axis of the pivot of said section.

The numeral 18 indicates a heavy electric sadiron of any suitable type and has a longitudinally extended tubular handle 19 rigidly secured to a heavy core in the form of a rod 20, the end portions of which, outward of said handle, are journaled in a pair of upstanding ears 21 on a plate 22 rigidly secured to the top of the sadiron 18. Headed screws 23 applied to the ends of the rod 20 hold said rod in the ears 21 against endwise 80 removal therefrom with the handle 19 closely positioned between said ears with freedom for turning movement about the axis of said rod.

To support the sadiron 18 out of contact 85 with the table top 15 when not in use, there is provided a pair of laterally spaced lazy tongs 24. These lazy tongs 24 are connected at their intermediate joints and held laterally spaced by horizontal rods 25, the ends of 90 which afford the pivots for said joints. These lazy tongs 24, at their rear ends, are mounted in a pair of latterly spaced standards 26 on the turnable table top section 16. The upper rearmost links in the lazy tongs 24 95 are pivoted to a shaft 27 mounted on the standards 26 and have formed therewith in bell-crank arrangement rearwardly extended arms 28 for a purpose that will presently appear. The lower rearmost links in the 100 lazy tongs 24 are attached to the standards 26 below the shaft 27 for compound pivotal and vertical sliding movements in vertical slots formed in said standards.

The sadiron 18 is attached by a heavy 105 hinge 29 to the front ends of the lazy tongs 24 for free ironing action on the table top 15 and for longitudinal tilting movement on its heel into a raised position in which it is supported from said lazy tongs above the 110

table top for free swinging movement thereover. This hinge 29 includes a rearwardly extended horizontal hinge plate 30 on the heel of the sadiron 18, a wide oblique hinge plate 31 attached to the front rod 25, and a horizontal pintle 32 connecting said plates. The hinge plate 30 is mounted in a recess 33 in the heel of the sadiron 18 and is pivoted to said iron at 34 to permit horizontal angular movements of the sadiron 18 on the table top 15 in respect to the hinge 29.

To hold the hinge plate 31 from turning on the rod 25 to which it is attached and in a rearwardly inclined position from the pintle 32, there is rigidly secured to the back of said plate a horizontal rearwardly extended rod 35 endwise slidably mounted in an apertured depending ear 36 on one of the rods 25. Obviously, this rod 35 holds the hinge plate 31 for parallel movements during the straightening and buckling movements of the lazy tongs 24.

To raise the sadiron 18 from the table top 15 by tilting the same on the pintle 32 and holding the same raised, as shown in Fig. 4, so that the sadiron 18 is out of contact with the table top 15 and may be freely swung over the surface thereof, there is provided a coiled spring 37 and a toggle lever 38 mounted between the prongs of the bifurcated lower end portion of the hinge plate 31. The lower arm 39 of the toggle lever 38 is integrally formed with the hinge plate 30 at the pintle 32 and is in bell-crank arrangement with said plate. The other or upper arm 40 of the toggle lever 38 comprises telescopically connected members, the outer of which is pivoted at 41 to the hinge plate 31.

The coiled spring 37 encircles the toggle arm 40 and is compressed between upper and lower washers 42 on the members of said toggle arm 40, at the opposite ends thereof. When the sadiron 18 is supported on the table top 15 for ironing action, the members of the toggle lever 38 are straight and the spring 37 is held compressed between the washers 42, as best shown in Fig. 8. To raise the sadiron 18, the operator by means of the handle 19, slightly tilts said sadiron on the pintle 32 to move the toggle lever 38 beyond a dead center and thereby release the spring 37 so that it will exert a force sufficient to tilt the sadiron 18 to a position, as shown in Fig. 4, and thus hold the same. During this action of the spring 37, the upper washer 42 affords a base of resistance therefor and the toggle member 38 is forced down to lift the point of the sadiron 18 until the heel thereof is above the table top 15.

Obviously, by taking hold of the handle 19, to and fro movements may be imparted to the sadiron 18, and at which time the lazy tongs 24 will be alternately buckled and

straightened during the ironing action. The pivot 34 also permits the sadiron 18 to be angularly moved to direct its point over the article being ironed. Said sadiron 18 may also be moved laterally in either direction over the table top 15 due to the fact that the lazy tongs 24 are attached to the turnable table top section 16, which will be swung by said lazy tongs under the lateral movement of said sadiron. 75

When the operator is through ironing, it is only necessary to lift the front end of the sadiron 18 from the table top 15 to move the toggle lever 38 beyond a dead center to release the spring 37 and thereby cause the same to lift the sadiron 18 so that the same is out of contact with said top and may be swung into a position at one side of the table top 15 where it is out of the way. 80

Obviously, the connections to the sadiron 18 from the turnable table top section 16 permit universal movement of the sadiron 18 on the table top 15 so that all classes and kinds of ironing may be accomplished in the same manner with a sadiron as now used. 90 As the work of lifting the sadiron to and from a stand has been eliminated by the use of the above described invention, a much heavier iron can be used, thus facilitating the ironing action. 95

To mechanically impart the to and fro movements to the sadiron 18 during the ironing action thereof, by oscillating the arms 28 and thereby imparting the straightening and buckling movements to the lazy tongs 24, there is mounted on the table top section 16 an electric motor 43 having on its armature shaft a worm 44 which meshes with a gear 45 on a horizontal longitudinally extended shaft 46 journaled in bearings 47 on said section. On the shaft 46 is a worm 48 which meshes with a gear 49 on a transverse stub shaft 50 journaled on the table top section 16. A face friction wheel 51 is keyed to the stub shaft 50. Co-operating with the face friction wheel 51 is a peripheral friction wheel 52 keyed to a shaft 53 for axial sliding movement thereon and which shaft 53 is journaled in bearings 54 on the table top section 16. 105

Keyed to the shaft 53 is a gear 55 which meshes with a vertically movable rack 56 having at its upper end a laterally projecting roller stud 57 which extends through a slot 58 in the front end portions of the arms 28 which are drawn together, as shown in Fig. 3. The rack 56 works in a long depending sleeve bearing 59 on the under side of the table top section 16, and a roller 60 engages the back of the rack 56 and holds the same for straight line movement and in mesh with the gear 55. This roller 60 is journaled on a stud on a bearing bracket 61 secured to the table top section 16. 110

When the peripheral friction wheel 52 is 130

at the axis of the face friction wheel 51, the driving connections from the motor 43 to the arms 28 is idle. By shifting the peripheral friction wheel 52 to one side of the axis 5 of the face friction wheel 51, the driving connections from the motor 43 will be operated to straighten the lazy tongs 24 and impart a forward movement to the sadiron 18, and by shifting said friction wheel 52 to 10 the other side of said axis, said connections will be operated to buckle the lazy tongs 24 and thereby impart a backward movement to said iron 18.

To shift the peripheral friction wheel 52 15 on the face friction wheel 51, the turnable handle 19 of the sadiron 18 is provided with a segmental gear 62 which is secured to the rear end of the rod 20 for oscillatory movement transversely of the sadiron 18. This 20 segmental gear 62 meshes with a pinion 63 on a rearwardly inclined tubular shaft section 64, the lower end of which is journaled in a sleeve bearing 65 on the top of said iron 18 at the heel thereof. A shaft section 66 25 is telescoped into the shaft section 64, and is square in cross section to connect said two shaft sections for common rotation with freedom for endwise movement in respect to each other.

30 The shaft section 66 is connected by a universal joint 67 to the forward end of a horizontal shaft section 68 which extends through aligned apertures in the rods 25 with freedom for endwise movement, and its rear end 35 portion is telescoped into a tubular shaft section 69, the rear end of which is journaled in a bearing 70 on a bearing bracket 71 secured to the table top section 16. The shaft section 68, within the shaft section 69, 40 is a square in cross section and connects said shaft sections 68 and 69 for common rotation. On the rear end of the shaft section 69 is a worm 72 which meshes with a worm gear 73 journaled on the bearing bracket 71 45 and is provided with a crank-acting shipper arm 74 having pivoted thereto a loop-like link 75 mounted in the annular channel of a shipper collar 76 on the peripheral friction wheel 52.

50 Obviously, the link 75 is free to move transversely of the shipper collar 76 during the oscillatory movements of the shipper arm 74. From the above description, it is evident that by turning the handle 19, the 55 peripheral friction wheel 52 may be moved axially on the shaft 53.

The length of the to and fro movements imparted to the sadiron 18 from the motor 43 is controlled by the operator while guiding said sadiron simply by turning the handle 19 to move the peripheral friction wheel 52 over the face friction wheel 53.

What I claim is:

1. The combination with a table having an 65 ironing surface, of a support, a sadiron hav-

ing a handle by which pressure may be applied thereto, said sadiron being carried by the support for movement over the ironing surface and out of contact therewith, said sadiron being movable on the support into 70 a position in which it rests on the ironing surface for ironing action, motor-actuated connections for moving the support to impart to and fro movements to the sadiron, and manually-controlled connections 75 arranged to be actuated by the handle of the sadiron for causing the motor-driven connections to reverse their movements.

2. The combination with a table having 80 an ironing surface, of a support, a sadiron carried by the support for movement over the ironing surface, a toggle connecting the sadiron to the support, one link of the toggle being rigid with the sadiron and the other link thereof being pivoted to the support 85 and comprising telescopically connected members, and a coiled spring encircling the link pivoted to the support and under strain to separate the telescopically connected members thereof, said toggle being straight 90 when the sadiron is resting on the ironing surface to hold the spring compressed, said toggle being arranged to be buckled by an initial tilting movement of the sadiron from the ironing surface to release the spring and 95 permit the same to complete the tilting movement of the sadiron to lift the same from the ironing surface.

3. The combination with a table having 100 an ironing surface, of a sadiron, motor-driven connections for imparting to and fro movements to the sadiron on the ironing surface including a face friction wheel and a cooperating peripheral friction wheel, and connections controlled by a manually-operated member on the sadiron for moving the peripheral friction wheel on the face friction wheel.

4. The combination with an ironing table 110 having a turnable section, of a pair of lazy tongs mounted on said section for horizontal swinging movement over the ironing table, a sadiron pivotally attached to the lazy tongs for ironing action on said table, manually-controlled means for tilting the sad iron out of contact with the ironing table to support the same for the lazy tongs, and motor-driven means on said section for operating the lazy tongs to impart to and fro movements to the sadiron for ironing action on the 115 ironing table.

5. The combination with a table having an 120 ironing surface, of a support, a sadiron attached to the support for movement from an operative position on the ironing surface to a tilted inoperative position out of contact with said surface, and a tilting device for the sadiron normally held inactive and arranged to be thrown into action by the initial tilting movement of the sadiron to com- 130

plete the tilting movement thereof and hold the sadiron in a tilted position.

6. The structure defined in claim 5 in which the tilting device is arranged to be thrown out of action by the movement of the sadiron from a tilted to an operative position.

7. The structure defined in claim 5 in which the tilting device is spring actuated.

10 8. The combination with a table having an ironing surface, of a support, a sadiron hinged to the support for movement from an operative position on the ironing surface to a tilted inoperative position out of contact with said surface, and a tilting device for the sadiron comprising a lever extension on the sadiron, and a spring compressed between said extension and the support, said extension and spring normally being on a dead center to render the tilting device active by the initial tilting movement of the sadiron to complete the tilting movement thereof and yieldingly hold the sadiron in its tilted position.

15 9. The combination with a table having an ironing surface, of a support, a sadiron

hinged to the support for movement from an operative position on the ironing surface to a tilted inoperative position out of contact with said surface, a tilting device for the sadiron comprising a toggle connecting the sadiron to the support, and a spring under strain to buckle said toggle and tilt the sadiron, normally said toggle in on a dead center and holds the spring inactive.

30

35

10 10. The combination with an ironing table, of a pair of lazy tongs mounted on the table for horizontal swinging movements thereover, a sadiron pivotally attached to the lazy tongs for movement to and from a position in which it rests on the ironing table to a tilted position out of contact with the ironing table, and a spring-actuated tilting device for the sadiron normally held inactive and arranged to be thrown into action by the initial tilting movement of the sadiron to complete the tilting movement thereof and yieldingly hold the sadiron in its tilted position.
